UNITED STATES PATENT OFFICE

LOUIS LEITZENBERGER, OF IRVINGTON, NEW JERSEY

CLOTHES DRIER

Application filed March 6, 1928. Serial No. 259,450.

This invention relates to apparatus for drying clothes and is especially adapted for use in situations where the space available for such purposes is limited.

Apparatus of the general type herein disclosed have been found desirable in apartment houses where it is customary to fasten vertical portions of such an apparatus to parts of a window frame and support outwardly extending rods in various positions by means of struts hinged to the vertical portions and slidably connected with the rods, the parts being releasably held in positions of adjustment by various devices which have been found inconvenient, since the manipulating of the adjusting means requires an operator to reach out of a window at more than arm's length.

It is an object of this invention to provide a clothes drying apparatus equipped with adjusting means which are simpler and more easily manipulated than heretofore has been the case with apparatus of this type.

A further object is to provide a clothes drying apparatus comprising relatively few parts, and adapted to be conveniently folded to an out-of-the-way position when not in use.

These and other objects will more fully appear from the following description and the accompanying drawing which form a material part of this disclosure, and in which:

Figure 1 is a perspective view of the apparatus folded to an out-of-the-way position.

Figure 2 is a sectional view taken on line 2-2 of Figure 1.

Figure 3 is a sectional view showing the position of parts of the apparatus to facilitate the hanging of clothes thereon.

Figure 4 is a sectional, side elevational view of the apparatus in extended position.

Figure 5 is a side view showing, on an enlarged scale, the latching device in its latched position.

Figure 6 is a similar view showing the latching device in its unlocked position.

Figure 7 is a view showing the latching device disassembled.

Referring to the drawings, the clothes drying apparatus is shown to comprise a pair

of vertical sheet metal bars 7 adapted to be fixed to opposite sides of a window frame as shown. Pivoted to each bar at 8 is a sheet metal bar 9, the pair of bars 9 being appropriately spaced by the rods 10 fixed to the outer ends of bars 9. The rods 10, as do the rods 11, fixed to intermediate portions of bars 9, strengthen and increase the rigidity of the structure.

Bars 9 are provided with a plurality of apertures through which ropes 26 may be passed to provide lines to which clothes to be dried may be attached.

Each supporting bar 7 has pivoted thereto at 12 a strut 13, which is adapted to adjustably hold the bar 9 in several positions of adjustment by means of the latching device mounted on bar 9.

This latching device comprises a metal block 14 provided with a groove having a width and depth equal to the width and thickness of strut 13. The lower section of the block is slotted at 15, and a disc 16 rests against the lower flange 17 of the block. The bolt 18 passes through the aperture in disc 16, the slot in block 14, and the bar 9, and the parts are securely held to the bar 9 by the nuts 19.

In order to make the device somewhat resilient a compression spring 20 is interposed between the head of bolt 18 and the disc 16. In assembling the apparatus, the strut 13 is positioned in the groove in block 14, and the latching device is then secured to bar 9.

Strut 13 is provided with a bent end portion 21 which limits the downward movement of bar 9, and the notches 22, 23, 24, 25 enable the adjusting of the bars 9 to various desirable positions. Notch 22 holds bar 9 in a horizontal position when the clothes have been hung upon the apparatus to dry. Notch 24 holds the bar in a raised position to facilitate the attaching of clothes to the outer portions of the apparatus, and notch 23 allows the bar 9 to be positioned to facilitate the attaching of clothes to the inner portions. When it is desired to fold the apparatus to an out-of-the-way position, notch 25 is used.

From the drawings it will be seen that the bolt 18 engages the notches to hold the bar

in the desired positions, and when it is desired to have the strut 13 slide freely through block 14, the block is moved upward to raise strut 13 to disengage bolt 18 from one of the 5 notches, the slot 15 allowing the upward movement of the block 14.

In operation, bolt 18 is positioned in notch 24, the block 14 being pressed downward to hold it in that position, and the apparatus 10 appears as shown in Figure 3. In this position clothes are attached to the outer ropes.

The block 14 is then pressed upward to release the latch, and bolt 18 is allowed to engage notch 23 to facilitate the attaching 15 of clothes to the inner ropes. After the clothes have been hung upon the ropes of the apparatus, the latch is released to allow bolt 18 to engage notch 22, and block 14 is pressed downward to securely hold bar 9 in a horizontal 20 position as shown in Figure 4.

After the clothes have been dried, the operations are reversed, and the apparatus may be held in an out-of-the-way position by allowing pin 18 to engage notch 25. (See Figure 1).

From the above description it will be seen that I have provided a clothes drying apparatus which may be more easily manipulated than heretofore has been the case with 30 similar apparatus.

The above disclosure is to be regarded as descriptive and illustrative only, and not limitative or restrictive of the invention, of which, obviously, modifications may be made 35 without departing from the scope of the appended claims.

Having described my invention what I claim as new and desire to protect by Letters Patent is:

40 1. In a clothes drying apparatus having an outwardly extending bar and a strut adapted to support said bar in various positions of adjustment, a latching device comprising a block having a groove through which the strut is slideable, a disc engaging the outer side of the block, a bolt passing through the disc and block to secure them to the bar, means on the lower edge of the strut adapted to engage the bolt, and a slot 45 in the block to enable transverse movement of the block relative to the bar to raise the strut from engagement with the bolt.

50 2. In a clothes drying apparatus having a bar and a strut adapted to hold the bar in a position of adjustment, a bolt carried by said bar and adapted to engage a notch in an edge of the strut, and means engaging said strut and slidably mounted on the bolt to move the strut from engagement with the 55 bolt.

60 3. In a clothes drying apparatus having a bar and a strut adapted to support the bar in a desired position, a bolt carried by said bar and adapted to engage a notch on the 65 lower edge of the strut, a block having a

groove through which the strut is slideable, said block being slidably mounted on the bolt so that the strut may be raised from engagement with the bolt.

4. In a clothes drying apparatus having a 70 bar and a strut adapted to support the bar in a desired position, a bolt carried by said bar and adapted to engage a notch on the lower edge of the strut, a block having a groove through which the strut is slideable, 75 said block being slidably mounted on the bolt so that the strut may be raised from engagement with the bolt, and means associated with the block and bolt to prevent the strut from moving out of the groove in the 80 block.

This specification signed this fifth day of March, 1928.

LOUIS LEITZENBERGER.
